US0D1102872S

(12) **United States Design Patent** (10) **Patent No.:** **US D1,102,872 S**
(45) **Date of Patent:** **** Nov. 25, 2025**

(54) **RV KEY**

(71) Applicant: **NINGBO SHENGJIU TECHNOLOGY CO., LTD.**, Yuyao (CN)

(72) Inventors: **Yao Chunliang**, Yuyao (CN); **Hu Jing**, Yuyao (CN)

(73) Assignee: **NINGBO SHENGJIU TECHNOLOGY CO., LTD.**, Yuyao (CN)

(**) Term: **15 Years**

(21) Appl. No.: **29/959,741**

(22) Filed: **Aug. 27, 2024**

(30) **Foreign Application Priority Data**

May 9, 2024 (CN) 202430270126.5
